EASEL

Gordon E. Nichols, Middleboro, Mass., assignor to
 Winthrop-Atkins Co., Inc., Middleboro, Mass., a
 corporation of Massachusetts

Application March 9, 1946, Serial No. 653,337

17 Claims. (Cl. 40—152.1)

1

This invention pertains to easels, and relates more especially to an easel for holding photographs or the like. For this purpose it is desirable that the easel have a finely finished and ornamental appearance and preferably that it have provision for protecting the photograph, for example by means of a glass or other transparent cover panel. It is also desirable to be able to fold the easel substantially flat when not in use, and likewise that it be possible to install or remove the photograph after the easel itself is fully complete. Furthermore, the photograph should be retained securely in position after it is once inserted, and unless purposely removed.

The present invention has for its object the provision of an easel, preferably a foldable easel, designed securely to hold a photograph or the like, and so arranged that the photograph may be installed and readily removed. A further object is to provide an easel having a chamber for the reception of the photograph, and having a transparent cover panel, and wherein the entrance to the chamber is normally concealed but readily exposed when desired. A further object is to provide an easel comprising a body portion which houses a movable carriage for the photograph and its transparent protective panel, the carriage having an actuating element arranged at the rear of the easel, whereby the carriage may be moved from a normal position to a position which facilitates the introduction or removal of the photograph. A further object is to provide an easel comprising a body portion which houses a slideable carriage having a chamber for the reception of the photograph, the chamber having an entrance at one end and wherein the entrance to the chamber in the carriage is normally concealed by a part of the body portion of the easel, and wherein the easel has a foldable leg which constitutes a handle for moving the carriage. Other and further objects and advantages of the invention will be pointed out in the following more detailed description, and by reference to the accompanying drawings wherein

Fig. 1 is a front elevation of the easel of the present invention, with certain parts broken away, showing the movable carriage in its normal operative position;

Fig. 2 is a rear view of the easel with the parts disposed as in Fig. 1, the easel being folded flat;

Fig. 3 is a diagrammatic transverse section, to large scale, on the line 3—3 of Fig. 1;

Fig. 4 is a view similar to Fig. 1, but showing the movable carriage in its upper position;

Fig. 5 is a rear view of the easel folded flat, showing the parts as disposed in Fig. 4;

2

Fig. 6 is a plan view showing the inner or front side of the back ply of the easel body before assembly with the other parts;

Fig. 7 is a plan view showing the inner or rear side of the front ply of the easel body, showing it disposed upon a cover sheet and before the latter has been folded;

Fig. 8 is a rear view of a combined spacer and retainer for the movable carriage;

Fig. 9 is a front elevation of the body portion of the easel after its parts have been assembled;

Fig. 10 is a plan view of a blank employed in making the movable carriage, showing the front member of the blank disposed upon a cover sheet, and before the latter has been folded over;

Fig. 11 is a plan view of an intermediate member or screen forming part of the carriage;

Fig. 12 is a front elevation of the carriage after completion;

Fig. 12a is a side elevation of the modified mount shown in Fig. 14; Fig. 12b is a section on the line 12b—12b of Fig. 16;

Fig. 13 is a diagrammatic vertical section, substantially on the line 13—13 of Fig. 12, but to larger scale;

Fig. 14 is a front elevation of an easel of modified construction;

Fig. 15 is a view similar to Fig. 14, but showing the cover element of the carriage raised to expose the rear member of the carriage.

Fig. 16 is a view similar to Fig. 15, but illustrating the way in which the carriage may be assembled with the body portion of the easel; and

Fig. 17 is an edge elevation of the carriage and cover member removed from the easel.

Referring to the drawings (Figs. 1 to 9), the numeral 1 designates a substantially rigid generally rectangular panel constituting the body portion of the easel. This body portion comprises a front ply 2 (Figs. 3 and 9), and a rear ply 3 (Figs. 3 and 6), spaced apart to provide for the reception of the movable carriage K. The front ply 2 has a window aperture W (Fig. 7) defined

by the parallel side edges 4 (Fig. 1), the top edge 5 and the bottom edge 6. The rear ply 3 (Fig. 6) is provided with a central aperture 7 and with an integral brace member 8 (Figs. 2, 5 and 6) projecting upwardly into this aperture, the brace member having a slot S of generally T-shape (Fig. 6), and initially being in the plane of the part 3. The front and rear plies 2 and 3 are bound together by means of a cover sheet 9 (Figs. 1 and 3) which is secured to the exposed surfaces of the plies 2 and 3 by means of adhesive.

This binding or cover sheet may be of any suit-

able material, for example paper, thin ornamental leather, cloth, or the like, and not only binds the front and rear plies together, but provides the desired external finish.

Interposed between the front and rear plies there is a combined guide and retainer device comprising a guide part 10 (Figs. 3 and 8) of substantially the same outside dimensions as the front ply 3 and having a window aperture W¹ (Fig. 8) which may be somewhat larger than the window aperture W in the front ply, and which is bounded by the parallel side edges 15, the bottom edge 12 and the top edge 14. The retainer member 11 is of the same outside dimensions as the part 10, and also has a window aperture, but this aperture is of somewhat smaller dimensions than the aperture W¹, being bounded by the parallel side edges 16 (Fig. 8), the top edge 13 and a bottom edge which coincides with the edge 12 of the guide member 10. The retainer 11 may, if desired, be united to the guide member 10, for example, by means of staples R or by adhesive, although it is not necessary to unite these parts before assembly with the front and rear plies. The retainer member 11 is disposed against the inner or rear face of the front ply 2, and the plies 2 and 3 are thereafter united by means of the binder sheet 9, as above suggested. The parts 2, 11, 10 and 3 may be directly united by adhesive if desired, as well as by the adhesively coated binder member 9. The edges 15 of the member 10 constitute guides for a movable carriage K, hereafter described, while the inner portions of the member 11, which overlap the edges 13 and 15, form a retainer for the carriage. The coincident edges 12 of the members 10 and 11 constitute a lower stop for the carriage, while the edge 13 constitutes an upper stop for the carriage.

The carriage K (Figs. 3 and 13) comprises the front member 17 (Fig. 10) having the window aperture D which is usually somewhat smaller than the window aperture W, so that when the carriage is in its normal position (Fig. 1) a portion of the carriage is exposed within the window aperture W to form a frame or mat for the picture. The front member 17 (Fig. 10) of the carriage is preferably integrally joined with the back member 18 of the carriage, these parts being united along the fold line 19, which may be scored to facilitate bending. The window D in the part 17 is defined by the side edges 20, the top edge 21 and the bottom edge 22. The vertical height of this carriage, between its upper and lower outer edges, is greater than the distance between the bottom edge 12 and the top edge 14 (Fig. 8) of the retainer member 11, but is less than the distance between the edge 12 and the edge 13 of the guide member 10 of the easel so that the carriage, when assembled with the other parts, may be moved vertically between the stop edges 12 and 13.

The back member 18 of the carriage is furnished with an integral leg member 23 (Fig. 10) united with the main part of the back along the hinge line 24, where the material may be scored or indented to facilitate bending. The leg is here shown as provided with a central aperture 25, and with an integral tongue 26 projecting down from the upper edge of this aperture. Preferably the carriage includes an intermediate member or screen 27 (Figs. 11 and 13) of an area substantially equaling that of the front member 17 of the carriage, and which is interposed between the front member and the back member

so as to conceal the inner surface of the back member with its apertured leg 23.

In assembling the parts (Fig. 13) the front member 17 and back member 18 of the carriage are bent along the line 19, the intermediate member or screen 27 is disposed between them, and then the binding or cover sheet 26^a is adhesively applied so as to bind the side and top edges of the constituent parts of the carriage together. If desired, a transparent panel G of glass, Celluloid, or the like, may be arranged to engage the inner surface of the front member 17. When the parts are thus assembled, they provide between them a chamber 28, for the reception of a photograph or the like, this chamber having an open entrance 29 at its lower end.

In assembling the easel as a whole, the front member 2 of the body portion of the easel is laid upon the binder sheet 9 (Fig. 7) and the inner marginal flaps 9^a of this cover sheet are turned in about the inner edges of the window W, and adhesively secured to the rear side of the front member 2. The combined spacer device, including the parts 10 and 11, is now disposed against the rear surface of the front member, the carriage is disposed with its side edges in contact with the edges 15 of the guide member 10, the rear member 3 of the body of the easel is placed over the carriage, and the flaps 9^b of the binding sheet are drawn around the edges of the assembly and secured to the rear surface of the rear member 3. Preferably a cover sheet 30 (Fig. 6) is secured to the inner or front surface of this rear member before assembly, and before the flaps 9^a are secured to the rear surface of the rear member 3, a cover sheet 31 (Figs. 2 and 5) is glued to the rear surface of the member 3. The cover sheet 30 serves to give a finished appearance to the front side of the backboard by hiding the incising made along the top and sides of the brace.

In order to insert a photograph into the chamber 28 of the carriage, the operator holds the body portion of the easel with one hand and with the other grasps the leg 23 and moves the latter upwardly relatively to the body portion of the easel. This causes the carriage K to slide upwardly along the guide elements 15 until the upper edge of the carriage contacts the stop 13. In this position the entrance 29 to the chamber 28 in the carriage is exposed (Fig. 4) above the lower edge 6 of the window W in the body portion of the easel. The photograph may now be slipped in through the window W and into the entrance 29 to the chamber 28, and properly adjusted therein so that it is correctly arranged when viewed through the window W. While in Fig. 13 the chamber 28 is indicated as of substantial depth from front to rear, the effect of the binding sheet 26 which extends around the sides and top of the carriage, is such that the glass panel G and the intermediate member or screen 27, are actually quite close together, so that when the photograph is pushed up between them it is frictionally retained in place. After the photograph has been introduced and properly arranged, the leg member 23 is pulled downwardly, thus restoring the carriage to its normal position in which the lower edge of the carriage contacts the stop edges 12 of the parts 10 and 11, the stop edges thus constituting a closure for the entrance opening 29 which is now below the edge 6 of the window W. The leg 23 may now be swung rearwardly and the brace 8 swung downwardly so as to hold the leg in operative position.

If it is desired to replace the photograph by another, the above operation may be reversed, the carriage being moved upwardly to expose the entrance 29 to the chamber 28, thus permitting the original photograph to be removed through the window W and replaced by another.

In the modified construction illustrated in Figs. 12a, 12b and 14 to 17 inclusive, the body 32 is comprised of the front ply 42, spacer 43, rear ply 44 and wrapper 45. The front ply is provided with the window aperture 33 having the spaced parallel lateral edges 34 and 35, the marginal portions of the window at its upper end being recessed as shown at 36 so as to increase the effective width of the window at this point.

The carriage comprises a thin panel portion 37 of rectangular contour and of a width slightly greater than the width of the lower portion of window 33. The forward face of this panel 37 constitutes a support for the device to be exhibited, for example, a photograph, or as here illustrated a pad 38 of paper, for instance a calendar.

While it is not essential that the carriage have a cover member, it is illustrated as having a cover flap 40 flexibly united or hinged at 41 to the upper edge of the panel 37. This cover flap is suitably finished to provide an ornamental appearance, and is of a width substantially as great as or slightly greater than the recessed upper part of the window 33. If desired this cover flap 40 may be provided with a pocket or cavity in its forward face for the reception of ornamental material, for example, a picture or the like, and if desired this cavity may be provided with a glass or other transparent cover 42.

The carriage is assembled with the body of the easel by inserting the lower edge 39 of the panel 37 in the widened upper part of the window 33 and sliding the panel 37 downwardly so that its edges are slipped behind the margins of the window 33 until the panel occupies the position shown in Fig. 15. The cover flap 40 may now be allowed to drop down so as to conceal the pad 38, the picture within the cavity in the cover flap giving an ornamental effect. However, when the user wishes to observe the pad 38, the cover flap 40 is turned upwardly so as to expose the pad to view. The carriage may readily be moved upwardly relatively to the body 32 of the easel, and entirely removed if desired, for example in order to facilitate replacement of the pad 38.

In the above description reference has been made to a photograph as the part to be exhibited through the window W of the easel, but it is to be understood that the easel is likewise useful for exhibiting any other thin sheet-like article and that when reference is made to a "photograph" it is to be understood that this is merely by way of convenience in description and not limiting as to the utility of the easel here described.

The easel of Figs. 14 to 17 may be provided with a leg and brace as illustrated in Figs. 12a and 16. As therein shown an easel is attached to the upper edge of the rear ply and a brace, Fig. 16, is struck out from the rear ply and extends rearwardly thereof into engagement with the easel, Fig. 12, and is interlocked therewith by a tongue and slot connection as shown in the previous figures.

While certain desirable embodiments of the invention have been illustrated by way of example, it is to be understood that the invention is broadly inclusive of any and all modifications falling within the scope of the appended claims.

I claim:

1. An easel comprising a body portion having a window therein, a carriage housed within the substance of the body portion, the carriage having therein a chamber for the reception of a photograph, the chamber being closed at its sides and at one end and having an entrance at its opposite end, the body portion having means for guiding the carriage to slide vertically, and means for moving the carriage relatively to the body portion from a position in which the entrance end of the carriage is exposed at the window in the body portion to a position where said entrance end is concealed behind the margins of the body portion bordering said window.
2. An easel comprising a body portion having a window therein, a carriage housed within the substance of the body portion, the carriage having therein a chamber for the reception of a photograph, the chamber being closed at its sides and at one end and having an entrance at its opposite end, the body portion having means for guiding the carriage to slide vertically, and means accessible at the rear side of the body portion for moving the carriage relatively to the body portion from a position where the entrance end of the carriage is accessible through the window, to a position in which the entrance end of the carriage is concealed behind the margins of the body portion bordering the window.
3. An easel comprising a body portion having a window therein, a carriage housed within the substance of the body portion, the carriage having therein a chamber for the reception of a photograph, the chamber being closed at its sides and at one end and having an entrance at its opposite end, the body portion having means for guiding the carriage to slide vertically, a leg for holding the easel in upright position, said leg being connected to the carriage and constituting a handle for moving the carriage relatively to the body portion from a position where the entrance end of the carriage is accessible through the window to a position where said entrance end is concealed from view.
4. An easel comprising a body portion having a window therein, a carriage housed within the substance of the body portion, the carriage having therein a chamber for the reception of a photograph, the chamber being closed at its sides and at one end and having an entrance at its opposite end, the body portion having means for guiding the carriage to slide vertically, a foldable leg for holding the easel in upright position, and a brace for the leg attached to the back of the body portion, the leg being so connected to the carriage that when the leg is in folded position it constitutes a handle for sliding the carriage relatively to the body portion.
5. An easel comprising a substantially rigid body portion having a window aperture therein, a carriage and means for guiding it to slide vertically relatively to the body portion, the carriage having therein a chamber for the reception of a photograph, the carriage having a window at its front which may be registered with the window aperture in the body portion, the carriage having an entrance at its lower end to admit a photograph to be introduced into the chamber, the carriage being closed at its sides, and means for moving the carriage relatively to the body portion from a position in which the entrance to the chamber is exposed through the window aperture to a position where said entrance is con-

sealed behind the lower margin of the window in the body portion.

6. An easel comprising a substantially rigid body portion, including a front ply having a window aperture therein, a rear ply spaced from the front ply, and a carriage disposed between said plies, the body portion including guide means for the carriage designed to allow the carriage to slide relatively to the body portion, the carriage having therein a chamber for a photograph, the carriage having a window at its front which normally registers with the window in the front ply of the body portion, the carriage being constructed and arranged to provide an entrance to said chamber at an edge of the carriage, and means for moving the carriage relatively to the body portion from a position in which said entrance to the chamber is exposed through the window in the front ply of the body portion to a position in which said entrance is concealed behind the marginal portion of the front ply bordering the window in the latter.

7. An easel comprising a substantially rigid body portion, including a front ply having a window therein, a rear ply spaced from the front ply, and a carriage disposed between said plies, the body portion including guide means for the carriage designed to allow the carriage to slide vertically relatively to the body portion, said guide means being so constructed and arranged that the carriage may slide upwardly from its normal position, but not downwardly, the carriage having therein a chamber for the reception of a photograph and having a window at its front which normally registers with the window in the front ply of the body portion, the carriage being provided at its lower end with an entrance to said chamber which is normally concealed below the margin of the front ply of the body portion bordering the lower edge of the window in the latter, and means for moving the carriage upwardly until the entrance to the chamber is exposed above the lower edge of the window aperture in the body portion.

8. An easel comprising a substantially rigid body portion, including a front ply having a window therein, a rear ply spaced from the front ply, and a carriage disposed between said plies, the body portion including guide means for the carriage designed to allow the carriage to slide vertically relatively to the body portion, said guide means comprising parallel side members which engage the side edges of the carriage, and stop means to limit upward and downward movement of the carriage respectively, the carriage having a window at its front, the lower stop means being arranged to limit downward movement of the carriage to a position such that the carriage window is normally registered with the window in the front ply of the body portion, the upper stop means being so arranged that the carriage may be moved upwardly from normal position, the lower end of the carriage being designed to provide an entrance to said chamber, and means for moving the carriage upwardly until said entrance is exposed above the lower edge of the window in the body portion.

9. An easel comprising a substantially rigid body portion including a front ply, a rear ply, and spacer means interposed between said plies, the front ply having a window therein, a carriage interposed between the front and rear plies of the body portion, said carriage having a chamber therein for the reception of a photograph and having a front window, said spacer means

being constructed and arranged to define a guideway for the carriage, the carriage being slideable in said guideway, the spacer means also defining upper and lower stops for limiting sliding movement of the carriage, the lower stop being arranged to position the carriage with its window in registry with the window in the front ply of the body portion and the upper stop being arranged to permit the carriage to move upwardly from normal position, the carriage having an entrance to its chamber at its lower end, and a foldable leg secured to the carriage and projecting through an aperture in the rear ply of the body portion, said leg constituting a handle by means of which the carriage may be slid vertically relatively to the body portion.

10. An easel comprising a substantially rigid body portion including a front ply, a rear ply, and spacer means interposed between said plies, the front ply having a window therein, a carriage interposed between the front and rear plies of the body portion, said carriage having a chamber therein for the reception of a photograph and having a front window, said spacer means comprising guide elements which engage the opposite edges respectively of the carriage, and retaining means overlapping the front face of the carriage, the guide elements being of such length as to permit the carriage to move from a normal position with its window registered with the window in the front ply of the body portion to a position in which the lower edge of the carriage is exposed through said window, the chamber in the carriage being open at the lower edge of the carriage to permit introduction of a photograph into the chamber, and a foldable leg secured to the carriage, said leg extending rearwardly through an aperture in the rear ply of the body portion and constituting a handle for moving the carriage.

11. An easel comprising a substantially rigid body portion including a front ply, a rear ply and spacer means interposed between said plies, said spacer means providing spaced parallel grooves between the plies, the front ply having a window therein, a carriage interposed between the front and rear plies of the body portion, said carriage constituting a support for a photograph independently of the body portion and having lateral portions which are disposed between the plies and which slidably engage the grooves so that the carriage is slideable vertically relative to the body portion, limit stop means situated between the plies below the lower edge of the window arranged to support the lower edge of the carriage at such heightwise position with respect to the body portion that the photograph carried thereby is in registration with the window and the lower edge of the carriage is concealed between the plies, and a foldable member hinged to the carriage and constituting a handle by means of which the carriage may be slid relative to the body portion.

12. An easel comprising a substantially rigid body portion including a front ply, a rear ply and spacer means interposed between said plies, said spacer means providing spaced parallel grooves between the plies, the front ply having a window therein, a carriage interposed between the front and rear plies of the body portion, said carriage constituting a support for a photograph independently of the body portion and having lateral portions which are disposed between the plies and which slidably engage the grooves so that the carriage is slideable vertically relative to the

body portion, limit stop means between the plies below the lower edge of the window arranged to support the lower edge of the carriage at such a heightwise position with reference to the body portion that the photograph is registered with the window and the lower edge of the carriage is concealed between the plies, said limit stop means being constituted by a portion of the spacer extending transversely of the lower end of the body portion between the plies, and a foldable member hinged to the carriage and constituting a handle by means of which the carriage may be slid relative to the body portion.

13. An easel of the kind described in claim 11, wherein the margins of said window have recesses which add to the effective width of the window near its upper end, which afford access to the spaced parallel grooves and through which the lower end of the carriage may be introduced into said spaced parallel grooves.

14. An easel of the kind described in claim 11, wherein a cover flap is hinged to the upper end of the carriage.

15. An easel of the kind described in claim 11, wherein a cover flap is hinged to the upper end of the carriage and is of such dimensions that when it is disposed in normal position from the upper end of the carriage it covers and conceals the window aperture in the panel.

16. An easel as described in claim 11, wherein a paper pad is fixed to the front side of the carriage, and a cover flap is hinged to the upper edge of the carriage, said cover flap normally concealing the paper pad and having an ornamental front face.

17. An easel as described in claim 11, wherein a paper pad is fixed to the front face of the carriage, and a cover flap is hinged to the upper edge of the carriage and normally depends therefrom so as to conceal said paper pad, the cover flap having a glazed chamber for the reception of a photograph.

GORDON E. NICHOLS.
